UNITED STATES PATENT OFFICE.

WILLIAM RAMSEY JACOBS, OF COMMERCE, TEXAS.

IRONING-BOARD.

1,092,444.

Specification of Letters Patent. Patented Apr. 7, 1914.

Application filed March 23, 1912. Serial No. 685,895.

To all whom it may concern:

Be it known that I, WILLIAM R. JACOBS, a citizen of the United States, residing at Commerce, in the county of Hunt and State of Texas, have invented a new and useful Ironing-Board, of which the following is a specification.

This invention relates to improvements in what are termed ironing boards.

10 The invention has for its object to provide certain facilities and conveniences for expediting the ironing operation.

15 A further object is to provide for suitably collapsing or folding the contrivance in compact form for conveniently storing or disposing the same when not required for use.

20 A still further object is to carry out the aforesaid objects in a simple, ready and effective manner.

25 The invention consists of certain instrumentalities and features substantially as hereinafter fully disclosed and defined by the claim hereto appended.

30 In the accompanying drawing, illustrating the preferred embodiment of my invention wherein, it will be understood that various changes and modifications may be made as to the detailed construction and arrangement of the parts without departing from the spirit thereof.

Figure 1 is an elevational view of the device. Fig. 2 is an end elevation of the same. Fig. 3 is a horizontal section taken on the 35 line $\alpha-\alpha$ of Fig. 1, viewing downwardly. Fig. 4 is a fragmentary sectional view, showing more particularly the tenon and socket or mortise like connection between one end of the underneath shelf and the front leg or standard of the device. Fig. 5 is a collapsed or folded view of the contrivance. Fig. 6 is a section taken on the line $y-y$ of Fig. 1. Figs. 7 and 8 are detail views illustrating the hinge connections of the shelf and treadle respectively to the folding structure.

45 In putting my invention into practice, I provide a board or table 1 of preferred or convenient construction and suitably supported in elevated position, preferably upon three standards or legs 2 and 3 respectively, the standards or legs 2 and 3 being preferably pivoted in position to allow of the folding or collapsing thereof.

50 The board or table 1 has an aperture 4 in one end to receive a projection 5 upon the upper end of the standard or leg 3, and has

secured thereto at, or near, its opposite end, upon the underside, a transverse bar 6, as seen in Fig. 6, the same terminating in end trunnion-like projections or pivots 7 received within sockets or seats 8 preferably formed in enlargements of the upper ends of the legs or standards 2, one of these standards having fixed thereto at its upper end, a sad iron stand or support 9. Thus, 60 applying or securing the table or board 1 in place allows of its ready removal and replacement according to circumstances or requirements.

The standards or legs 2 and 3 are pivoted 70 in position between, and upon the two converging base-members 10, the forward standard or leg 3 itself terminating at its lower end in a cross bar or foot 11, adapted to rest upon the floor, the other legs or standards 75 2, which are devoid of transverse feet-forming portions as characterize the leg 3, receive trunnion-like projections or tenons of a rung or cross bar 12, said projections passing loosely through said longitudinal members 10, near their rear ends. The pivotal connection between the opposite ends of said longitudinal members 10 and the leg 3 is preferably effected by a pin or pivot 13 inserted transversely therethrough. 85

A shelf 14, which may be a plain board, for forming a convenient support for a damp cloth or other object, is hinged as at 14^a near one end to a cross, or rung-like, bar 15 secured to, and between the legs or 90 standards 2 near their upper ends, the opposite end of said shelf-forming board having a tenon 16 thereon received by a socket 17 in the standard or leg 3. A hook and staple connection is employed for the suitable retention of the tenon 16 in its socket 95 17 in the leg 3, the hook, designated as 18, being connected to the shelf or board 14 and the staple, designated as 19, being secured to said leg. 100

A diagonal brace 20 is hinged as at 20^a at one end, to the board or shelf 14 upon its underside, near one end, the opposite end of said brace having a tenon 21 thereon, received by a socket 22. A hook and staple connection is also provided between the brace 20 and the leg or standard 3, for the retention of the tenon 21 in its socket, the hook, designated as 23, being connected to the brace and the staple, designated as 24, 110 being secured to said leg.

Superposed with respect to the ironing

board 1, is a sleeve-board 25, the same being adapted for suitable insertion into the sleeve of a garment and having fixed to its underside a foot 26 adapted to rest upon the first 5 referred to board, near one end thereof, for its support in elevated position above the latter. Said sleeve-board has also connection with the ironing board by means of a link or frame 27, preferably rectangular in 10 outline, said link or frame being adapted to be slipped into a transverse groove 28, indenting the upper surface of a stub-like portion or extension 29 of the sleeve-board 25 and caught over the less cross sectional 15 portion of a stepped extension 30 of the board 1, the shoulder formed by the major cross section of said stepped extension serving to limit the movement of said link or frame inwardly. This arrangement allows 20 of the ready application of the sleeve-board to position upon the board 1, and its ready removal therefrom, when not needed for use.

A treadle, including a lever 31, is suitably hinged or fulcrumed as at 32 from the rung or cross bar 12, between the legs 2, one end of said lever having preferably 25 stiff-wire connection 33, through a staple 34, with the board 1, said staple being secured to, and depending from the extension 30 of said board and said connection 33 being hooked into said staple as at 35, allowing of the ready detachment of the wire connection from said board or rather its 30 staple. The opposite end of the lever 31 is suspended by a link-connection 36 from a foot-actuated member 37 suitably ful-

crumed as at 38 from the member 10, said lever and foot-actuated member constituting the treadle, by the suitable actuation of 40 which the board 1 may be thus elevated off the standard or leg 3 to allow of the ready slipping thereon of a garment or article it may be desired to "iron."

It is apparent from the foregoing that 45 the assemblage of parts described may all be readily collapsed or folded when not needed for immediate use and be conveniently stored out of the way, also that they may be shipped with advantage and facility. 50

What is claimed is:

A device of the character described, including a folding structure, and means for holding the same extended, including a shelf having one end hingedly connected to the structure, coöperating means carried by the other end of the shelf and the adjacent portion of the structure to detachably hold the shelf elevated, a brace having one end hingedly connected to the under side of the 60 shelf adjacent the hinged connection of the shelf to the folding structure, and coöperating means carried by the free end of the brace and the adjacent portion of the structure to detachably hold the brace in operative position. 65

In testimony that I claim the foregoing as my own, I have hereto affixed my signature in the presence of two witnesses.

WILLIAM RAMSEY JACOBS.
